A. LINDNER.
SPINDLE ADJUSTING MECHANISM.
APPLICATION FILED AUG. 7, 1916.

Patented July 10, 1917.

Inventor:

By Arthur Lindner,
Robert W. Tawelle,
Attorney.

Adelaide Kearns,

UNITED STATES PATENT OFFICE.

ARTHUR LINDNER, OF RICHMOND, INDIANA, ASSIGNOR OF ONE-HALF TO FRED D. BETHARD, OF RICHMOND, INDIANA.

SPINDLE-ADJUSTING MECHANISM.

1,233,072.

Specification of Letters Patent. Patented July 10, 1917.

Application filed August 7, 1916. Serial No. 113,448.

To all whom it may concern:

Be it known that I, ARTHUR LINDNER, a citizen of the United States, residing in the city of Richmond, in the county of Wayne 5 and State of Indiana, have invented a new and useful Spindle-Adjusting Mechanism, of which the following is a full, clear, and comprehensive specification and exposition, the same being such as will enable others to 10 make and use the same with exactitude.

The object of my present invention, broadly stated, is to produce new and useful machine elements which will be strong and durable in construction, neat and attractive 15 in appearance, simple in arrangement and operation, compact as to space required therefor, which will greatly facilitate the accuracy of the work performed by the machine in which it is incorporated, and which 20 can be manufactured and utilized at a comparatively low price.

More specifically stated, my object is to provide a spindle adjusting mechanism for lathes, grinding machines, and other similar 25 tools, whereby the usual end play of the spindle or shaft will be entirely eliminated, and by which the usual wear incident to such devices may be compensated for, thereby permitting absolute accuracy in the work 30 produced thereby.

Other minor objects and particular advantages of the invention will be observed and brought out in the course of the following specification, and that which is new will 35 be correlated in the appended claims which terminate this specification.

The preferred means for carrying out my invention in a mechanical and a practical manner is shown in the accompanying drawings, in which—Figure 1 is a longitudinal central vertical section of the invention, showing the spindle in full-line elevation.

Fig. 2 is an end elevation of the parts shown in Fig. 1.

Fig. 3 is a detail plan view of the pulley and the adjusting collar connected thereto.

Fig. 4 is an elevation of the adjusting collar alone.

And Fig. 5 is a perspective view of the set-pin alone.

Similar indices denote like parts throughout the several views.

In order that the construction, the operation, and the advantages of my invention 55 may be more fully understood and appreciated, I will now take up a detailed descrip-

tion thereof, in which I will set forth the same as briefly and as comprehensively as possible.

Referring now to the drawings in detail, numeral 1 denotes the base of a machine, 60 which has two upwardly extending standards 2 and 3, carrying the respective heads 4 and 5, which latter have a horizontal aperture therethrough, which are in alinement with each other, and in which are secured 65 the respective bearings 6 and 7.

Extending through and fitting in said bearings is the spindle or shaft 8, which extends beyond the bearings at each end thereof. In this instance the ends of the spindle 70 are reduced in diameter, as at 9 and 10, and the major outer parts of the reduced portions are threaded, as at 11 and 12, to provide means for securing an emery wheel 13, or other tool, on one or both ends of the 75 spindle, as by means of the disks *a*—*b* and *c*—*d*, to be clamped in place by means of the respective nuts 14 and 15, as shown, or otherwise if desired.

Numerals 16 and 21 denote caps which fit 80 around the spindle 8 and close the outer ends of the apertures through the heads 4 and 5, pressing the felt rings 18 and 23 in contact with the bearings 6 and 7 and also into contact with the spindle 8.

In like manner the fiber washers 17 and 20 close the inner ends of the apertures through the heads, pressing the felt rings 19 and 22 in contact with the bearings and with the spindle.

Numerals 24 and 25 denote oilers for the spindle bearings.

The invention proper comprises the following devices: Letter A denotes the belt-pulley which is rigidly secured on and 95 around and concentric with the spindle by means of the pin B, or otherwise, the said pin being inserted at right-angles through the central portion of the pulley and through the shaft as indicated.

A flange D extends out from around one end of the pulley to prevent a belt from sliding off. The flanged end of the pulley contacts with the fiber washer 17, or some other stationary part of the machine. From 105 the opposite end of the pulley there extends the exteriorly threaded nipple E, which is integral with the pulley and it extends in an axial direction to near the fiber washer 20, or some other stationary part of the machine. The said nipple is of less diameter

than the body of the pulley, thereby forming a square shoulder as shown.

Letter F denotes the adjusting collar, which is in the nature of a round nut, and it is adapted to be screwed on the nipple E and it extends from said shoulder at the intersection of the pulley and the nipple to near the fiber washer 20. Formed in the face of the collar F are sockets G to receive 10 the prongs of a spanner wrench whereby the collar may be rotated independently of the pulley.

The locking means.—Formed in the center of the periphery of the collar F, and at 15 right-angles to the spindle, is the interiorly threaded socket H which is slightly deeper than is the length of the set-screw I which is adapted to be screwed therein. The socket H does not extend through the wall of the 20 collar F, but a smaller aperture J extends through from the center of the bottom of the socket H through the threads of the collar. Letter K denotes a set-pin which is adapted to slide in the aperture J and having 25 a head L which is slightly less than the diameter of the socket H in which it is located. The inner end of the set-pin is provided with threads M which are adapted to fit the threads of the nipple E when the set- 30 pin is pushed inward to its limit.

Modus operandi.

From the above it will be apparent that by loosening the set-screw I the collar F 35 may be turned upon the nipple E, thereby contacting the right-hand face of the collar against the fiber washer 20 and contacting the left-hand face of the pulley against the fiber washer 17, thereby taking up all of 40 the end play or endwise movement of the shaft. After the above mentioned adjustment has been made then the set-screw I should be run in or tightened, which will press the pin K inward thereby engaging 45 the threads M securely in mesh with the threads of the nipple E, and without injury thereto, which manifestly will lock the collar against inadvertent movement.

It is to be understood that I reserve the 50 right to make minor changes in the details of the invention, from that herein shown, and that the invention proper is not to be limited to the type or character of machine which is herein shown therewith.

Having now fully shown and described 55 my invention, what I claim and desire to secure by Letters Patent of the United States, is—

1. A spindle adjusting mechanism com-

prising in combination with two bearings 60 and a spindle mounted therein, a pulley rigidly secured to the spindle and located between said bearings, a threaded nipple projecting from one end of the pulley, and a collar threaded around on said nipple, all 65 substantially as shown and described.

2. A spindle adjusting mechanism comprising in combination with two bearing and 70 a spindle mounted in the bearings, a pulley secured around the spindle and located between said bearings, a nipple projecting from one end of the pulley, a collar threaded around on said nipple and adapted to move in an axial direction toward and from the pulley, and means for locking the pulley in its adjusted position, all substantially 75 as shown and described.

3. In combination with two spaced apart stationary elements and a shaft revolvably mounted in said elements, a pulley secured 80 around said shaft and located at one end in contact with one of said elements, a threaded nipple projecting in an axial direction from the other end of said pulley, a collar threaded around on said nipple and adapted 85 to project beyond the free end thereof to contact with the other element, all substantially as set forth.

4. In combination two spaced apart stationary elements and a shaft revolvably 90 mounted in said elements, a pulley secured around said shaft and between said elements and adapted to contact with one of said elements, a projection extending from one end 95 of the pulley and in an axial direction and to near the other one of said elements, a collar surrounding said projection and adapted to be moved parallel with the shaft and to contact with the other one of said elements, and means for locking said collar to 100 the projection.

5. A device of the character set forth, comprising in combination with a spindle; a pulley surrounding the spindle, means for securing the pulley to the spindle, a projection extending in an axial direction from one end of the pulley, a collar surrounding the projection and adapted to be moved endwise toward and from the pulley, and means for locking the collar upon the projection. 110

In testimony whereof I have hereunto subscribed my name to this specification in the presence of two subscribing witnesses.

ARTHUR LINDNER.
